UNITED STATES PATENT OFFICE.

MAXMILIAN ERNST, OF CLEVELAND, OHIO.

DESIGN FOR A BOX-COVER.

SPECIFICATION forming part of Design No. 25,005, dated December 24, 1895.

Application filed May 9, 1895. Serial No. 548,777. Term of patent 7 years.

To all whom it may concern:

Be it known that I, MAXMILIAN ERNST, a citizen of the United States, residing at Cleveland, in the county of Cuyahoga and State of Ohio, have invented and produced a new and original Design for Box-Covers, of which the following is a specification, reference being had to the accompanying drawings, forming a part thereof.

10 Figure 1 is a picture of a box-cover made according to my design. Fig. 2 is a central vertical section of the cover applied to the box *a*.

The box-cover *b* is hollow, to fit over the

box proper *a*, and the external surface of the 15 sides and top of the hollow cover have such configuration or outline as to form the outline of the head of Napoleon I.

What I claim is—

The design for a box-cover herein shown 20 and described.

In testimony whereof I sign this specification, in the presence of two witnesses, this 6th day of May, 1895.

MAXMILIAN ERNST.
